UNITED STATES PATENT OFFICE.

RICHARD G. LEDIG AND NIKOLAUS GERSON, OF PHILADELPHIA, PENNSYLVANIA,
ASSIGNORS TO A. MECKY COMPANY, OF PHILADELPHIA, PENNSYLVANIA, A COR-
PORATION OF PENNSYLVANIA.

GUARD FOR ELECTRIC HEATERS.

1,305,130.

Specification of Letters Patent. Patented May 27, 1919.

Application filed January 18, 1919. Serial No. 271,820.

To all whom it may concern:

Be it known that we, RICHARD G. LEDIG, a citizen of the United States, and NIKOLAUS GERSON, a subject of the Government of Austria, having resided in the United States one year last past and having declared my intention of becoming a citizen thereof, residing in the city and county of Philadelphia, State of Pennsylvania, have invented

10 a new and useful Guard for Electric Heaters, of which the following is a specification.

Our invention consists of a guard for an electric heater the same being composed of a series of arms, and a ring which latter centrally gathers and connects the former forming a strong, inexpensive, durable and practical device for the purpose intended.

The invention is satisfactorily illustrated in the accompanying drawing, but the important instrumentalities thereof may be varied, and so it is to be understood that the invention is not limited to the specific details shown and described, as long as they are within the spirit or scope of the claims.

25 Figure 1 represents a side elevation of a guard embodying our invention.

Fig. 2 represents a front elevation of the same on an enlarged scale.

30 Fig. 3 represents a rear view of the central portion of the guard on an enlarged scale.

Fig. 4 represents a somewhat similar view with a portion broken away.

Fig. 5 represents a perspective view of one of the arms of the guard.

35 Fig. 6 represents a transverse section on the line 6—6 Fig. 1.

Fig. 7 represents a blank from which the central ring of the guard is formed.

40 Fig. 8 represents a perspective view of said ring in primary condition.

Similar numerals of reference indicate corresponding parts in the figures.

Referring to the drawings.

45 1 designates a series of arms each of which is formed of a pair of divergent-curvilinear members 2 and the cross bar or head end 3 of said members, said bar joining the latter, the outer ends of said members being formed with lips 4 for attachment to a suitable portion of an electric heater, whereby the guard in its entirety is adapted to be set in front of the heater for well known purposes.

The arms 1 are connected in front with the ring 5, thus sustaining said arms, forming

together a hemispherical-shaped frame to 55 which shape we do not limit ourselves. Said ring consists of a body of annular form with clips 6 and 7 thereon respectively on the inner and outer peripheries of the body forming the circular channel 7, said lips alternating in the opposite circumferences. 60

The ring as thus far described is produced primarily from the blank 8 of suitable metal or material as shown in Fig. 7.

The arms are arranged or assembled to 65 radiate rearwardly from said ring and the cross bars 3 thereof are placed in the channel 7 when the portions of the arms adjacent to said cross bars extend radially from the ring between adjacent clips, the arms thus 70 being centered on said ring. Then the ring is subjected to a press whereby the inner and outer clips 6 are curled over said cross bars alternating in opposite directions and compressed thereon whereby they tightly 75 clamp said bars in opposite directions with a firm hold thereon, while the ends of the inner clips abut the adjacent portions of the respective arms and so interlock with the same as to retain the cross bars of the arms 80 steady in their mounting on the ring. The guard is now in condition for attachment to the proper part of an electric heater.

The arms 2 may be formed of sufficiently heavy wire or light round metal as desired 85

Having thus described our invention what we claim as new and desire to secure by Letters Patent, is:—

1. A guard of the character stated consisting of a series of arms, and a central ring, 90 the former radiating from the latter, said ring having therein a channel and on its periphery a series of clips which are adapted to clamp the head ends of said arms which are seated in said channel. 95

2. In a guard of the character stated, formed of a central ring and arms radiating therefrom, said ring being constructed of an annular body having therein a circular channel, and clips on the periphery of said body, 100 the head ends of said arms being adapted to be seated in said channel and held tightly clamped on said body by the engagement of said clips.

3. A guard of the character stated formed 105 of a ring and curvilinear arms which diverge from said ring and are seated therein, said ring being constructed of a body having

therein a circular channel in which the head ends of said arms are seated, and clips extending respectively on the outer and inner peripheries of said body and adapted to clamp said head ends of the arms on said body in opposite directions.

4. In a guard of the character stated, a ring having therein a channel, clips thereon and arms which are adapted to extend rear-

wardly from said ring, said arms having 10 their head-ends adapted to be seated in said channel and clamped by said clips.

RICHARD G. LEDIG.
NIKOLAUS GERSON.
